UNITED STATES PATENT OFFICE.

WILLIAM W. LASKER, OF BROOKLYN, NEW YORK, ASSIGNOR, BY MESNE ASSIGNMENTS, TO POWERS ACCOUNTING MACHINE CORPORATION, OF NEW YORK, N. Y., A CORPORATION OF DELAWARE.

MEANS FOR LOCKING AND ALIGNING TYPE SEGMENTS.

Original application filed March 28, 1917, Serial No. 158,142. Divided and this application filed April 3, 1918. Serial No. 226,496.

To all whom it may concern:

Be it known that I, WILLIAM W. LASKER, a citizen of the United States, residing in Brooklyn, in the county of Kings and State of New York, have invented certain new and useful Improvements in Means for Locking and Aligning Type Segments, of which the following is a specification.

This invention relates to a printing tabulator of the kind adapted to be controlled by perforated cards, and relates more particularly to matter divided from my co-pending application Serial No. 158,142 filed March 28, 1917, for printing tabulators.

The invention herein described relates particularly to the means for locking and aligning the type segments of said printing tabulator; and, therefore, only as much of the printing tabulator is described herein as is necessary to show the connection between the matter of the original application and the matter divided out and described herein.

While herein and in said application minute details of one of many possible embodiments of the invention are described, the invention is not limited to these since various changes may be made in the details of construction and combination without departing from the spirit and scope of the invention as claimed.

One object of the invention is to improve generally apparatus of this kind.

Another object of the present improvement is to construct a printing tabulator having an improved form of locking and aligning mechanism for the type segments, which will be efficient in operation and economical in structure.

Still further objects and advantages of the present improvement will be set forth in the following description and drawings in which,

Fig. 1 is a side elevation of the printing tabulator constructed in accordance with my invention.

Fig. 2 is a detail view of the locking and aligning bar.

Fig. 3 is a side elevation of a type segment and its actuating mechanism.

Fig. 4 is a plan showing the locking and aligning bar engaging the segments.

Fig. 5 is a side elevation of the stop pin box, showing shutter latches for holding the stop pins set. 55

Fig. 6 is an end elevation of Fig. 5.

In the said co-pending application means are shown for feeding perforated cards to an analyzer comprising a reciprocating pin box provided with the pins adapted to feel the cards and on finding perforations in the cards to pass through such perforations and to raise registering stops corresponding to perforations, the naught stop being normally raised and adapted by suitable connections to be depressed by the raising of a numeral registering stop. 60 65

Referring more particularly to the drawing of the present application, there are shown a plurality of numeral registering stops 10 (Fig. 3) of the kind just mentioned. These stops 10 are arranged in rows, and associated with each row is a naught stop 11 and a reciprocating rack bar. Each rack bar 12 is provided with a 70 75 downward projection 14 adapted to engage the rear face of a raised stop 10 or 11 as the rack is reciprocated forward (to the left, in Fig. 3) by a transverse bar 15, as will be explained. 80

This transverse 15 engages a drive shoulder 16 on a pivoted bar 18 pivoted at its forward end to the rack bar 12 and yieldably held in raised position by a spring 19 strained between its rear end and a 85 bracket 20 on the rear end of the rack bar 12.

Said pivoted bar, is normally held raised, as just stated, so that the shoulder 16 will be engaged by the transverse rack bar 15. 90 Said pivoted bar 18 is lowered from the normal position to the position shown in Fig. 3 by means of a small lever 21 pivoted at 22 to the rack bar 12, and provided with a slot 24 receiving a pin 25 fixed to the pivoted bar 18. The lower end of the lever 22 engages (as the rack bars and said levers are brought forward) whichever stop 10 or 11 is raised. At this instant, said lower end is raised and the slotted end of the lever 21 is lowered thereby lowering the pivoted bar 18 and the shoulder 16 thereon, thus permitting the transverse bar 15 to move on free from said shoulder, the rack 95 100

bar 12 being stopped by its shouldered projection 14 engaging behind said raised stop 10.

When the transverse bar 15 moves rearwardly, it engages the shoulder 26 formed on the rack bars 12 and moves all of the rack bars to their rearward position. This rearward movement takes place after the printing has taken place as will be explained.

The bar 15 which as heretofore described, is for the purpose of reciprocating the bars 12 and 18 is itself reciprocated in the following manner, reference especially being made to Fig. 1. The bar 15 which is rectangular in cross section is rigidly connected at each end to a slide 27, which is reciprocatable between rollers 28 forming guideways therefor. A slot 29 is made in each cheek plate 30 of the frame of the tabulating machine, and in this slot 29 is received a roller 31 revolvably mounted on the rear end of the said slides 27. The front end of the slides 27 are provided with horizontally extending pins 32, which are received in slots 33 formed in the upper ends of levers 34, the lower portion of which are triangularly shaped, one corner being pivoted to stud shafts 35, carried by each cheek plate 30. The other corner of the triangular shaped levers 34 carries rollers 36 which are arranged to roll within cam grooves made in the cam 38 on the shaft 44 (Fig. 4).

Returning now to the reciprocating bars, the top edge of the forward portion of the said bars 12 are provided with gear teeth 49 (Fig. 3) which are in mesh with a gear 50 secured to type segments 52, which have bearings on a transverse shaft 53 carried between the cheek plates 30. Said segments have an arc shaped rear edge provided with gear teeth 54 which will hereafter be described. The front edge of the segments 52 are also made arc shaped and have mounted thereon ten type 55. Reading from the upper edge of the type carrying portion of the segment, the type carried thereby read in sequence, the first type being zero, the next "1" the next "2" etc., the last type on the segment being numbered "9".

When the pins 10 have been set by perforated cards, as explained, and the transverse bar 15 has caused the forward movement of the rack bars 12 until they are stopped by the raised pins 10 or 11, the type segments are stopped with the type in printing position in accordance with the position of the raised pins 10 or 11. At this instant paper carried on a suitable paper carriage 60 is pressed against the type and the printing takes place. After the printing takes place the paper is fed one or more line spaces and is ready for

another imprinting. A suitable paper carriage is described in said co-pending application.

After all of the type segments have been set by the stop pins in position to print data transferred thereto from the cards, means is provided for locking and aligning the type segments so that they may not move during the printing operation. This locking and aligning means will now be described.

A lever 72 (Fig. 1) is provided having a bifurcated lower end 73 which straddles the main drive shaft 44 which provides the driving means, for the entire type setting and calculating mechanism. This lever 72 is provided with a pin 74 upon which is rotatably mounted a roller 75 which is arranged to roll within a cam slot 76 of a cam 77 (Fig. 4). The extreme upper end 80 of the lever 72 is provided with a knife shaped transversely extending arm 80 slidably mounted within a slot 81, within the cheek plates 30. Both the slot 81 and the knife shaped member 80, which is termed a detent, are arranged radial to the gear teeth 54 of the type segments and lock said segments from moving, and line up the type carrier thereby.

The lever 72 is also connected to suitable mechanism for returning all of the numeral stop pins to their normal position at the same time raising the naught stops 11. As these mechanisms are described in detail in said copending application, they need be here described only briefly as follows:

Means are provided for anchoring in raised position the various stop pins 10 as they are actuated, and for holding the zero stop 11 in position for stopping or permitting to pass the corresponding type setting and tabulating elements. This anchoring means comprises shutters 186 (Figs. 5) provided with end lugs 187 extending through openings 189 of the end plates 190. By means of these lugs 187 the shutters 186 are adapted to rock relative to the end plates. The upper edge of the shutters have an inclined edge 191 and a forwardly extending arm 192 that is turned at its extreme end to form a stop 193. Each of the shutters 186 is disposed adjacent to one row of stop pins 10 with its inclined edge 191 extending toward the pins. In order that the stop pins 10 and zero stops 11 be anchored by the inclined edges 191 they are provided with upper and lower notches 194 and 195, each forming at its upper edge a shoulder adapted to engage the inclined edge 191, so that the stops 10 will be supported on such inclined edge 191.

The lower edges of the notches are inclined to form cam faces over which the edges can ride with facility when the numeral stops 10 are raised. As one of the

stops 10 is raised the edge 191 of the shutter will engage the cammed face of the upper notch and will be forced outwardly sufficient to put the springs (hereafter to be described) which actuate the shutter 186 under sufficient tension to cause the said shutter to spring within the lower notch 195 when it has cleared the said cam face, and at the same time to move the shutters a sufficient distance to release the zero stops 11.

The edge 191 upon lodging within the lower notch 195 will maintain the stop 11 in a raised position.

For normally resiliently maintaining the said shutters in engagement with the stops 11, the springs 196 are provided, which are secured to the upper edge of a reciprocating plate 197 and extend downward into engagement with the extensions 193 as shown in Fig. 6, said springs 196 exercising a lateral pressure on the shutters 186 to press them into engagement with the stop pins 11. The rear side plate 190 is provided with openings 198, through which the said extensions 192 pass. The extensions 192 also pass through recesses 199 formed at the lower edge of the reciprocatable plate 197. The reciprocatable plate 197 is provided with recesses 200 through which extend screws 201, to permit the sliding of the plate 197. For normally maintaining the plate 197 rightward of Fig. 6, a coil spring 205 is provided which connects a stud 207 on the reciprocatable plate 197 with a stud 208 on the side plate 190.

The plate 197 is also provided with an extension 209 which extends through the cheek plate 30 and has a lower cam face 210 for engagement by the shutter release arm 211. The openings 199 in the side plate 190 are of sufficient width to permit the lateral movement of the extension 192, and the extensions 192 normally rest against one edge of the openings 199.

The release arm 211 is intermediately fulcrumed on a screw 212 (Fig. 1) in the cheek plate 30 and is provided at its motive end with a slot 214 receiving a pin 215 fixed on the side of the lever 72.

As the lever 72 moves downward to effect the locking and aligning of the type segments by the bar 80, the slotted end of the arm 211 is lowered and the active end of the arm is raised into engagement with the lower cam face 210 (Fig. 6) thus throwing back the plate 197 and forcing the sides of the recesses 199 against the extensions 192 and forcing back the shutters 186 from contact with the stop pins and releasing the latter to be lowered under the action of the springs 240 later to be mentioned.

The zero stops 11 are normally disposed in raised position and whenever a stop 11 is actuated to the raised position, simulta-

neously therewith the zero stop 11 in that row will be lowered. In order to accomplish this result an elongated lever 222 (Fig. 3) is provided for each row of stops 11, which lever is provided with a plurality of lugs 223 arranged in a straight line and extending into one of the recesses 224 of the stop pins 11. The front ends of the levers 222 are pivoted on a shaft 225 which is supported by the cheek plates 30. The rear ends of the lever 222 are provided with lugs 226 which slidably and pivotally engage in slots 227 at the rear ends of the links 228 pivoted on a shaft 229 supported by the cheek plates 30. The front end of the links 228 are provided with lugs 230 which are arranged to slide within a recess 231 formed in the rear edge of the nought stop 11.

Suitable springs 240 are provided for the purpose of normally holding the levers 222 down and raising the nought stops 11. When one of the stops 10 is raised, the actuation of the lever 222 by means of the cooperation of the slot 224 of the stop, with the lug 223 of the lever will cause the link 228 to be actuated which will in turn lower the zero stop 11 of the row in which the numeral stop pin 10 has been raised.

In view of the foregoing, it will be noted that the lowering of the numeral stop pins 11 and the raising of the zero stops cannot take place until the type segments are locked by the bar 80, since the same lever 72 which initiates the release of the shutters 186 also at the same time causes the locking of the segments. In this way there is no danger that the stop pins be lowered before the segments are locked.

I claim:

1. In an apparatus of the character described, the combination of type carriers provided with teeth; a plurality of rows of vertically movable stop pins each provided with a shoulder; pivoted shutters adapted to engage under the shoulder of any raised stop; a sliding plate adapted when actuated to move said shutters out of engagement with said shoulders and provided with a lower cam face; means controlled by said pins for positioning the carriers; a reciprocating locking bar adapted to be disposed between said teeth; a release arm engaging said cam face; and means for simultaneously and positively reciprocating the locking bar and the release lever.

2. In an apparatus of the character described, the combination of cheek plates; type carriers therebetween provided with teeth; a plurality of rows of vertically movable stop pins disposed between said cheek plates and each provided with a lateral shoulder; a pivoted shutter spring-pressed against each row and adapted to engage under the shoulder of any raised stop; a transverse sliding plate adapted when actuated

to move said shutters out of engagement with said shoulders and provided with an extension projecting through a cheek plate and having a lower cam face; means controlled by said pins for positioning the carriers; a reciprocatory locking bar adapted to be disposed between said teeth; and a release arm intermediately fulcrumed on one of said cheek plates and having one end engaging under said lower cam face; and means for simultaneously positively reciprocating the locking bar and the release lever.

3. In an apparatus of the character described, the combination of a pair of cheek plates each provided with a guide slot; type segments each provided with teeth; a knife member guided in said guide slots and adapted to engage said gear teeth; rotary cams; longitudinally movable levers connected to said knife member and operated by said cams.

4. In an apparatus of the character described, the combination of type carriers provided with teeth; a reciprocatory locking bar adapted to engage between said gear teeth; a cam shaft a pair of rotary cams thereon; a pair of levers having their upper ends fixed to said bar and having their lower end bifurcated and straddling said shaft; and means on each lever and engaging in one of said cams.

5. In an apparatus of the character described, the combination of a pair of cheek plates each provided with a bearing opening and a guide slot; a shaft in said openings; type segments on said shaft each provided with teeth; a knife member having its end parts guided in and projecting from said guide slots, and adapted to engage between said teeth; a cam shaft a pair of rotary cams thereon; levers having their upper ends fixed to said end parts and their lower ends bifurcated and straddling said shaft; and rollers on the levers and engaging the cams.

6. In an apparatus of the character described, the combination of a pair of cheek plates each provided with a bearing opening and a guide slot radial to said opening; a transverse shaft in said openings; a plurality of type segments on said shaft and each provided with a plurality of gear teeth; rows of settable stop members; means controlled by said members for positioning the segments; means for anchoring the pins in set position; a transverse knife shaped member having its end parts guided in and projecting from said guide slots, and having its edge adapted to engage between said gear teeth; a cam shaft; a pair of rotary cams thereon and each provided with a cam groove; a pair of levers having their upper ends fixed to said end parts and having their lower ends bifurcated and straddling said

shaft; a roller on each lever and engaging in one of said grooves; and means operated by said levers for releasing the anchoring means.

7. In an apparatus of the character described, the combination of type carriers provided with teeth; rows of settable stop members; means controlled by said members for positioning the carriers; means for anchoring the members in set position; a reciprocatory locking member adapted to be disposed between said teeth; a pair of rotary cams; levers actuating said locking member and actuated by said cam; a pin projecting from one of said levers; and a release arm positively operating said anchoring means and provided with a slot receiving said pin.

8. In an apparatus of the character described, the combination of type carriers provided with teeth; rows of settable stop members; means controlled by said members for positioning the carriers; means for anchoring the members in set position and comprising a releasing plate having a cam face; a reciprocatory locking bar adapted to be disposed between said teeth; a pair of rotary cams; a pair of levers being secured to said bar and operated by said cam; a pin projecting from one of said levers; and an intermediately fulcrumed release arm having one end engaging under said cam face and the other end provided with an end slot receiving said pin.

9. In an apparatus of the character described, the combination of type carriers; a reciprocatory locking member adapted to lock said carriers; a cam each provided with a cam groove both side walls of which are active; and means engaging in said groove and positively operating said locking member.

10. In an apparatus of the character described, the combination of type carriers provided with teeth; a reciprocatory locking bar adapted to engage between said teeth; a pair of rotary cams each provided with a cam groove both side walls of which are active; a pair of levers having their upper ends secured to said bar; and a roller on each lever and engaging in said grooves respectively.

11. In an apparatus of the character described, the combination of type carriers provided with teeth; rows of settable stop members; means controlled by said members for positioning the carriers; means for anchoring the members in set position; a reciprocatory locking bar adapted to be disposed between said teeth; a pair of rotary cams each provided with a cam groove both sides of which are active; a pair of levers having their upper ends secured to said bar; a roller on each lever and engaging in said grooves respectively; and means operated

by one of said levers for positively releasing the anchoring means.

12. In combination, cheek plates each provided with a bearing opening and a guide slot radial to said opening; a transverse shaft in said openings; type segments on said shaft and each provided with a plurality of gear teeth; a plurality of rows of vertically movable stop pins disposed between said cheek plates and each provided with a lateral shoulder; means controlled by said pins for positioning the segments; a pivoted shutter spring pressed against each row and adapted to engage under the shoulder of any raised notch; a transversely sliding plate adapted to move said shutters out of engagement with said shoulders and provided with a cam face; a transverse knife member guided in said guide slots, and engaging between said gear teeth; a cam shaft; rotary cams thereon and each provided with a groove; levers having their upper ends fixed to said knife member and having their lower ends bifurcated and straddling said shaft; rollers on the levers and engaging in said grooves; a pin projecting from one of said levers; and a release arm fulcrumed on one of the cheek plates and engaging said came face and provided with an end slot receiving said projecting pin. 30
13. In an apparatus of the character described, the combination of type carriers; settable members adapted to position the carriers; and means adapted to lock said carriers and to act positively to restore the settable members before the carriers are unlocked and restored to their initial position. 35
14. In an apparatus of the character described, the combination of type carriers; settable members adapted when set for stopping the carriers in printing position; and means adapted to lock said carriers in said position and to simultaneously to act positively to restore the settable members. 40
